(57) **ABSTRACT**

Provided is an elongated housing which allows easy maintenance without being separated from the device body. The elongated housing, which is accommodated in a device body so that a lengthwise direction thereof becomes a first direction, includes a plurality of first rollers and a plurality of second rollers disposed on a first surface of the elongated housing to be arranged in a row along the first direction; and a plurality of third rollers and a plurality of fourth rollers disposed on a second surface of the elongated housing to be arranged in a row along the first direction, wherein the elongated housing is movably supported between a first state of being accommodated in the device body and a second state of being drawn from the device body in the first direction.

**ELONGATED HOUSING, SUPPORT
INSTRUMENT OF ELONGATED HOUSING,
AND LIGHT IRRADIATION DEVICE**

TECHNICAL FIELD

The present disclosure relates to an elongated housing (for example, a light irradiation device for irradiating a line-shaped light, an ink-jet head, or the like) included and used in a device body, a support instrument thereof, and a light irradiation device.

BACKGROUND ART

In the prior art, an ultraviolet (UV) curable ink which is cured by irradiation of ultraviolet rays is used as an ink for an offset sheet-fed printing or an ink-jet printer. To cure the ultraviolet curable ink, an ultraviolet ray irradiation device for irradiating ultraviolet rays is generally used, and regarding the use of printing particularly, since light should be irradiated to an irradiation region elongated in a direction (namely, a width direction of a paper) perpendicular to a transporting direction of a printing paper, a ultraviolet ray irradiation device elongated in a width direction of a paper for irradiating a line-shaped light is used.

As an ultraviolet ray irradiation device, a lamp-type irradiation device using a high-pressure mercury lamp or a mercury xenon lamp as a light source is known, and recently, according to the demands on reduced power consumption, longer life cycle and compact device size, an ultraviolet ray irradiation device using a light emitting diode (LED) as a light source, instead of an existing discharge lamp, has been developed. This ultraviolet ray irradiation device is disclosed in, for example, Patent Literature 1.

The ultraviolet irradiation device (ultraviolet irradiation unit) disclosed in Patent Literature 1 includes a plurality of ultraviolet light emitting semiconductor elements in plural rows, and is installed in a printing device with a posture in which a lengthwise direction of the ultraviolet irradiation unit is in a direction (namely, a width direction) perpendicular to a transporting direction of a printing medium. Since the printing device is configured to print with four-color UV inks of black (K), cyan (C), magenta (M) and yellow (Y), the printing device includes four printing units respectively corresponding to the colors, and four ultraviolet irradiation devices for curing inks, respectively, and these components are disposed along an outer circumference of a drum which transports a printing medium.

DISCLOSURE

Technical Problem

In each ultraviolet ray irradiation device disclosed in Patent Literature 1, since it is preferred to irradiate ultraviolet rays which are approximately perpendicular to a printing medium and have high irradiation intensity, the ultraviolet ray irradiation device is positioned and fixed to be inclined in a printing device so that an emission surface is close to a printing medium. However, in the ultraviolet ray

2

irradiation device used in such a printing device, since the scattered ink or the gas generated in curing an ink may contaminate the emission surface and deteriorate irradiation intensity, periodic maintenance is required, and thus in case of the constitution disclosed in Patent Literature 1, there is no sufficient work space between the emission surface and the printing medium, and maintenance may not be performed if each ultraviolet ray irradiation device is not separated from the printing device. In addition, once each ultraviolet ray irradiation device is separated from the printing device, a complicated positioning work is required for mounting the ultraviolet ray irradiation device again, and if maintenance is performed for all ultraviolet ray irradiation devices, long time is required and downtime of the printing device increases.

The present disclosure is designed in consideration of the above, and the present disclosure is directed to an elongated housing included and used in a device body, like a light irradiation device, and provides an elongated housing allowing easy maintenance without being separated from the device body, a support instrument of the elongated housing comprising it, and a light irradiation device allowing easy maintenance without being separated from the device body.

25 Technical Solution

In one general aspect, in order to achieve the purpose described above, the present disclosure provides an elongated housing, which is accommodated in a device body so that a lengthwise direction thereof becomes a first direction, the elongated housing comprising: a plurality of first rollers and a plurality of second rollers disposed on a first surface of the elongated housing to be arranged in a row along the first direction; and a plurality of third rollers and a plurality of fourth rollers disposed on a second surface of the elongated housing to be arranged in a row along the first direction, wherein each of the first rollers and each of the third rollers has a rotary shaft extending in a second direction perpendicular to the first direction and rotates on the 30 rotary shaft, wherein each of the second rollers and each of the fourth rollers has a rotary shaft extending in a third direction perpendicular to the first direction and the second direction and rotates on the rotary shaft, wherein the first surface and the second surface are parallel to the second direction or the third direction, and wherein the elongated housing is movably supported between a first state of being accommodated in the device body and a second state of being drawn from the device body in the first direction.

40 In this configuration, since the elongated housing may be 50 easily drawn from the device body, maintenance may be easily performed.

In addition, when being observed in the first direction, the rotary shaft of each of the first rollers and the rotary shaft of each of the third rollers may be disposed on the same line.

55 In addition, when being observed in the first direction, the rotary shaft of each of the first rollers and the rotary shaft of each of the third rollers may be disposed on different lines.

In addition, a roller surface of each of the second rollers may protrude further in the second direction in comparison 60 to a roller surface of each of the first rollers, and a roller surface of each of the fourth rollers may protrude further in the second direction in comparison to a roller surface of each of the third rollers.

In addition, the number of the plurality of first rollers and 65 the number of the plurality of third rollers may be identical, the number of the plurality of second rollers and the number of the plurality of fourth rollers may be identical, the

plurality of first rollers and the plurality of third rollers may be disposed symmetrically with the elongated housing being interposed therebetween, and the plurality of second rollers and the plurality of fourth rollers may be disposed symmetrically with the elongated housing being interposed therebetween.

In addition, in another aspect, the present disclosure provides a support instrument of an elongated housing, which includes the elongated housing described above, the support instrument comprising: a first guide rail disposed in the device body to accommodate and support the plurality of first rollers and the plurality of second rollers; and a second guide rail disposed in the device body to accommodate and support the plurality of third rollers and the plurality of fourth rollers.

In addition, in the support instrument of an elongated housing, at least one of the plurality of first rollers and the plurality of second rollers may come into contact with an inner surface of the first guide rail, and at least one of the plurality of third rollers and the plurality of fourth rollers may come into contact with an inner surface of the second guide rail.

In addition, in another aspect, the present disclosure provides a light irradiation device, which is accommodated in a device body and extends in a first direction on a predetermined irradiation surface in the device body to irradiate a line-shaped light having a predetermined line width in a second direction perpendicular to the first direction, the light irradiation device comprising: a substrate; a plurality of light sources arranged on the substrate at predetermined intervals along the first direction to match an optic axis thereof in a third direction perpendicular to the first direction and the second direction; a box-type case configured to accommodate the substrate and the plurality of light sources; a plurality of first rollers and a plurality of second rollers arranged on a first surface of the case in a row along the first direction; and a plurality of third rollers and a plurality of fourth rollers arranged on a second surface of the case in a row along the first direction, wherein each of the first rollers and each of the third rollers has a rotary shaft extending in the second direction and rotates on the rotary shaft, wherein each of the second rollers and each of the fourth rollers has a rotary shaft extending in the third direction and rotates on the rotary shaft, wherein the first surface and the second surface are parallel to the second direction or the third direction, and wherein the case is movably supported between a first state of being accommodated in the device body and a second state of being drawn from the device body in first direction.

In addition, in the light irradiation device, the device body may include a first guide rail configured to accommodate and support the plurality of first rollers and the plurality of second rollers; and a second guide rail configured to accommodate and support the plurality of third rollers and the plurality of fourth rollers.

In addition, in the light irradiation device, the plurality of light sources may be arranged to have M (M is an integer of 2 or above) light sources along the first direction and to be in N rows (N is an integer of 2 or above) along the second direction.

In addition, in the light irradiation device, the light may have a wavelength giving an effect to an ultraviolet curable ink.

Advantageous Effects

As described above, according to the present disclosure, an elongated housing allowing easy maintenance without

being separated from a device body, a support instrument of the elongated housing comprising it, and a light irradiation device allowing easy maintenance without being separated from a device body are implemented.

DESCRIPTION OF DRAWINGS

FIG. 1 is a diagram showing an example of a case where an elongated housing according to an embodiment of the present disclosure and a support instrument thereof are applied to a light irradiation device and an offset sheet-fed printing device including the same.

FIG. 2 is a diagram for illustrating a configuration of a light irradiation device according to an embodiment of the present disclosure.

FIG. 3 is a diagram for illustrating a configuration of each LED unit of the light irradiation device according to an embodiment of the present disclosure.

FIG. 4 is a diagram for illustrating a state where the light irradiation device according to this embodiment is mounted to an offset sheet-fed printing device.

FIG. 5 is a diagram for illustrating configurations of a first roller and a second roller of the light irradiation device according to an embodiment of the present disclosure.

FIG. 6 is a diagram for illustrating a state where the light irradiation device according to an embodiment of the present disclosure is accommodated in an offset sheet-fed printing device and a state of being drawn in an X-axis direction.

FIG. 7 is a diagram for illustrating a modification of the light irradiation device according to an embodiment of the present disclosure.

FIG. 8 is a diagram for illustrating a modification of the light irradiation device according to an embodiment of the present disclosure.

FIG. 9 is a diagram for illustrating a modification of the light irradiation device according to an embodiment of the present disclosure.

FIG. 10 is a diagram for illustrating a modification of the light irradiation device according to an embodiment of the present disclosure.

FIG. 11 is a diagram for illustrating a modification of the light irradiation device according to an embodiment of the present disclosure.

BEST MODE

Hereinafter, the embodiments of the present disclosure will be described in detail with reference to accompanying drawings. Meanwhile, in the drawings, identical or corresponding portions will be endowed with the same reference numeral and not described repeatedly.

FIG. 1 is a diagram showing an example of a case where an elongated housing according to an embodiment of the present disclosure and a support instrument thereof is applied to a light irradiation device 100 and an offset sheet-fed printing device 1 including the same. In addition, FIG. 2 is a diagram for illustrating a configuration of a light irradiation device 100 according to an embodiment of the present disclosure, where FIG. 2(a) is a plane view showing the light irradiation device 100, observed in a Z-axis direction, FIG. 2(b) is a cross-sectional view taken along the line B-B of FIG. 2(a), and FIG. 2(c) is an enlarged view showing a portion A of FIG. 2(a). As shown in FIG. 1, the light irradiation device 100 of this embodiment is an elongated housing included in plural in the offset sheet-fed printing device 1 to cure an ultraviolet curable ink of each color, and a light source device for outputting line shaped ultraviolet

rays to a printing medium P. Meanwhile, in this specification, as shown in the coordinate of FIG. 2(a), an arrangement direction of a LED element 133 described later (namely, a lengthwise direction of the light irradiation device 100) is defined as an X-axis direction, a direction in which the LED element 133 emits ultraviolet rays is defined as a Z-axis direction, and a direction perpendicular to the Y-axis direction and the Z-axis direction (namely, a short direction of the light irradiation device 100) is defined as a Y-axis direction.

As shown in FIG. 1, the offset sheet-fed printing device 1 includes a feeding unit for feeding a sheet-shaped printing medium P into the offset sheet-fed printing device 1, a printing unit for printing a printing medium P while carrying the printing medium P, and a delivery unit for accommodating a printing medium P' printed by the printing unit in order. The printing unit includes printing units 201, 202, 203, 204 for transferring four-color ultraviolet curable inks of black, cyan, magenta and yellow onto the printing medium P, respectively, and four light irradiation devices 100 for curing an ultraviolet curable ink of each color, transferred onto the printing medium P by each of the printing units 201, 202, 203, 204.

As shown in FIG. 2, the light irradiation device 100 of this embodiment includes 45 LED units 130 arranged to have nine LED units along the X-axis direction to be in five rows along the Y-axis direction, a box-type case 101 accommodating the LED units 130, and the like. In addition, an ultraviolet ray emitted from each LED unit 130 is configured to output through a cover glass 102 installed at one surface of the case 101. Meanwhile, in FIG. 2(b), a dashed dotted line represents an optic axis of each LED unit 130, and the optic axis of each LED units 130 of this embodiment are configured so that the optic axes are intersected on the printing medium P (details will be described later).

FIG. 3 is a diagram for illustrating a configuration of each LED unit 130. FIG. 3(a) is a diagram showing the LED unit 130, observed in the Z-axis direction, FIG. 3(b) is a diagram showing the LED unit 130, observed in the Y-axis direction, and FIG. 3(c) is a cross-sectional view, taken along the line D-D of FIG. 3(b). As shown in FIG. 3, the LED unit 130 of this embodiment includes a metallic plate-shaped base plate 131 extending in the X-axis direction, a substrate 132 extending in the X-axis direction, ten LED elements 133 disposed on the substrate, a first lens 135 and a second lens 136 disposed in an optical path of each LED element 133, and a lens frame 134 having a "U"-shaped section (a section in the Y-axis direction) which extends in the X-axis direction, accommodates the first lens 135 and supports the second lens 136.

Ten LED elements 133 are disposed on the substrate 132 of this embodiment in a row in the X-axis direction at predetermined intervals, in a state of matching their optic axes in the Z-axis direction, and are electrically connected to the substrate 132. The substrate 132 is connected to an LED driving circuit, not depicted, and a driving current is supplied to each LED element 133 through the substrate 132 from the LED driving circuit. If a driving current is supplied to each LED element 133, ultraviolet rays of an intensity according to the driving current are output from each LED element 133, and line-shaped ultraviolet rays parallel to the X-axis direction are output from the LED unit 130. Meanwhile, in each LED element (133) of this embodiment, a driving current supplied to each LED element 133 of this embodiment is adjusted so that the LED elements 133 emit approximately the same intensity of ultraviolet ray, and the line-shaped ultraviolet rays emitted from the LED unit 130

have approximately uniform intensity distribution in the X-axis direction. Meanwhile, each LED element 133 of this embodiment includes an approximately square light emitting surface (not shown), and is supplied with a driving current from the LED driving circuit to emit ultraviolet rays having a wavelength of 365 nm.

The first lens 135 and the second lens 136 allows the ultraviolet rays emitted from the LED element 133 to extend in the X-axis direction so as to form a single line-shaped ultraviolet ray having a predetermined line width in the Y-axis direction.

As shown in FIGS. 3(a) to (c), the first lens 135 of this embodiment is a circular flat-convex lens having a flat first surface (a surface toward the LED element 133) and a spherical second surface (a surface toward the second lens 136). Each of the first lenses 135 have the same shape and optical characteristics respectively, and are fixed to be accommodated at a bottom of the lens frame 134 having a "U"-shaped section, so as to be located on the optical path 15 of a corresponding LED element 133.

The ultraviolet ray emitted from the LED element 133 is input to the first surface of the first lens 135 and is output from the second surface. If the ultraviolet ray emitted from the LED element 133 passes through the first lens 135 as described above, the ultraviolet ray is shaped to have a predetermined diffusion angle.

The second lens 136 is a toroidal lens having different refractive powers in the X-axis direction and the Y-axis direction respectively, and in this embodiment, a 10-consecutive mold toroidal lens in which ten second lenses 136 are connected in the X-axis direction. The second lens 136 is a plane rectangular flat-convex lens having a planar first surface (a surface toward the first lens 135) and a toroidal second surface (an emission surface). Each of the second lenses 136 have the same shape and optical characteristics 30 and are fixed to and supported by a front end of the lens frame 134 having a "U"-shaped section so as to be located on the optical path of a corresponding LED element 133.

The ultraviolet ray emitted from the LED element 133 and 40 passing through the first lens 135 is input to the first surface of the second lens 136, focused in the X-axis direction and the Y-axis direction, respectively, and output from the second surface. In addition, the ultraviolet ray emitted from each second lens 136 is overlapped with an ultraviolet ray emitted from an adjacent second lens 136 in the X-axis direction, and from the LED unit 130, a single line-shaped ultraviolet ray extending in the X-axis direction and having a predetermined line width in the Y-axis direction is output.

As shown in FIG. 2(a), in this embodiment, nine LED 50 units 130 are closely disposed successively in the X-axis direction. Since ultraviolet rays emitted from the nine LED units 130 arranged along the X-axis direction are overlapped in the X-axis direction at a joint portion to an adjacent LED unit 130, as described above, from the nine LED units 130 55 arranged along the X-axis direction (namely, nine LED units 130 in each row), a single line-shaped ultraviolet ray extending in the X-axis direction and having a predetermined line width in the Y-axis direction is output.

As shown in FIG. 2(b), in this embodiment, nine LED 60 units 130 are arranged in one row, and the LED units 130 are arranged in five rows along the Y-axis direction. For this reason, five line-shaped ultraviolet rays are emitted from the light irradiation device 100 of this embodiment, and five rows of the LED units 130 arranged in the Y-axis direction 65 are disposed in an arc shape, so that the line-shaped ultraviolet rays emitted from the LED units 130 of each row are overlapped with each other on the printing medium P.

The case 101 includes a metallic support member 150 elongated along the X-axis direction and having a concave arc surface with an arc shape with respect to the Z-axis direction, and five metallic cooling pipes 140 respectively elongated along the X-axis direction and arranged on the arc surface of the support member 150 along the Y-axis direction, therein. In addition, as nine LED units 130 of each row are fixed on each cooling pipe 140, five rows of the LED units 130 are disposed in an arc shape, and the line-shaped ultraviolet rays emitted from the LED units 130 of each row are overlapped with each other on the printing medium P. If the line-shaped ultraviolet rays emitted from the LED units 130 of each row are overlapped with each other on the printing medium P, ultraviolet rays of uniform and high irradiation intensity may be irradiated to ultraviolet curable inks transferred onto the printing medium P. By doing so, the ultraviolet curable inks on the printing medium P may be regularly cured. Meanwhile, a channel 142 through which a cooling water flows is formed in each cooling pipe 140, so that a cooling water is supplied from a cooling water supply means (not shown) connected to each channel 142, thereby cooling nine LED units 130 of each row. In addition, as shown in FIG. 2(c), in this embodiment, the LED units 130 of each row arranged along the Y-axis direction are disposed to be shifted along the X-axis direction in order as much as $\frac{1}{5}$ of an interval between LED elements 133 on the substrate 132. If the LED units 130 of each row are shifted along the X-axis direction, each of the LED elements 133 are uniformly disposed with respect to the X-axis direction, and thus irradiation intensity of ultraviolet rays overlapped on the printing medium P becomes approximately uniform in the X-axis direction. As described above, from the light irradiation device 100 of this embodiment, ultraviolet rays of uniform and high irradiation intensity are irradiated.

As described above, the light irradiation device 100 according to this embodiment is a device included in the offset sheet-fed printing device 1 to cure an ultraviolet curable ink on the printing medium P. Therefore, generally, in order to irradiate ultraviolet rays having as high irradiation intensity as possible to the printing medium P, each light irradiation devices 100 are disposed adjacent to the printing medium P. However, if each light irradiation device 100 is disposed adjacent to the printing medium P, scattered ultraviolet curable ink or gas generated in curing the ink may contaminate the cover glass 102 and deteriorate irradiation intensity, and thus periodic maintenance, such as mopping of the cover glass 102, is required. The maintenance may be easily performed if a sufficient work space is ensured around the cover glass 102, but in a situation where each light irradiation device 100 is disposed adjacent to the printing medium P, like the light irradiation device 100 according to this embodiment, it is difficult to ensure a sufficient work space around the cover glass 102. For this reason, in this embodiment, each light irradiation device 100 in the offset sheet-fed printing device 1 is configured so as to be drawn in the X-axis direction to solve the above problem.

FIG. 4 is a diagram for illustrating a state where the light irradiation device 100 according to this embodiment is mounted to the offset sheet-fed printing device 1, which shows a mounting state of a light irradiation device 100 located at a rightmost side in FIG. 1, observed in the X-axis direction. As shown in FIG. 2(a) and FIG. 4, the light irradiation device 100 of this embodiment includes five first rollers 110a to 110e and three second rollers 120a to 120c arranged in a row along the X-axis direction, on a side panel 101a of the case 101. The first rollers 110a to 110e respectively have rotary shafts 110ax to 110ex extending in the

Y-axis direction (in FIG. 4, the rotary shafts 110ax to 110dx are not shown), and serve as rotating members rotating thereon. In addition, the second rollers 120a to 120c respectively have rotary shafts 120ax to 120cx (not shown in FIG. 4) extending in the Z-axis direction, and serve as rotating members rotating thereon. In addition, the first rollers 110a to 110e and the second rollers 120a to 120c are configured to be inserted (accommodated) in a guide rail 10 installed in the offset sheet-fed printing device 1.

10 In addition, as shown in FIG. 2(a) and FIG. 4, the light irradiation device 100 of this embodiment includes five third rollers 111a to 111e and three fourth rollers 121a to 121c arranged in a row along the X-axis direction, on a side panel 101b parallel to the side panel 101a. Each of the third rollers 111a to 111e respectively have rotary shafts 111ax to 111ex (in FIG. 4, the rotary shafts 111ax to 111dx are not shown) extending in the Y-axis direction, and serve as rotating members rotating thereon. In addition, each of the fourth rollers 121a to 121c respectively have rotary shafts 121ax to 121cx (not shown in FIG. 4) extending in the Z-axis direction, and serve as rotating members rotating thereon. In addition, the third rollers 111a to 111e and the fourth rollers 121a to 121c are configured to be inserted (accommodated) in a guide rail 11 installed in the offset sheet-fed printing device 1. Meanwhile, in this embodiment, the first rollers 110a to 110e and the third rollers 111a to 111e are disposed at symmetric locations with the case 101 being interposed therebetween, and the second rollers 120a to 120c and the fourth rollers 121a to 121c are disposed at symmetric locations with case 101 being interposed therebetween (FIG. 2(a)).

As shown in FIG. 4, in this embodiment, when being observed in the X-axis direction, the rotary shafts 110ax to 110ex of each of the first rollers 110a to 110e and the rotary shafts 111ax to 111ex of each of the third rollers 111a to 111e are disposed on the same line, and the guide rail 10 and the guide rail 11 are disposed at both ends of the light irradiation device 100 along the Y-axis direction. Meanwhile, as shown in FIG. 4, the guide rail 10 and the guide rail 11 of this embodiment have an approximately "T"-shaped section since they have two-directional loads of the Y-axis direction and the Z-axis direction. In addition, when supporting a heavy and long article such as the light irradiation device 100, the guide rail 10 and the guide rail 11 may be deformed, which may cause the first rollers 110a to 110e, the second rollers 120a to 120c, the third rollers 111a to 111e and the fourth rollers 121a to 121c to deviate from the guide rail 10 and the guide rail 11. For this reason, in the guide rail 10 and the guide rail 11 of this embodiment, front ends of side surfaces 10b, 10d of the guide rail 10 and side surfaces 11b, 11d of the guide rail 11 are bent inwards to have an approximately "C"-shaped section. In addition, it is also possible that any one front end of the side surfaces 10b, 10d and any one end of the side surfaces 11b, 11d are bent inwards to have an approximately "J"-shaped section.

As described above, since the first rollers 110a to 110e and the second rollers 120a to 120c are accommodated in the guide rail 10 and the third rollers 111a to 111e and the fourth rollers 121a to 121c are accommodated in the guide rail 11, the light irradiation device 100 of this embodiment may be supported to be movable in the X-axis direction along the guide rails 10, 11. In addition, when the light irradiation device 100 is accommodated in the offset sheet-fed printing device 1 along the guide rails 10, 11 (namely, in a state of FIG. 4), the cover glass 102 of the light irradiation device 100 is positioned to face the printing medium P and allow the ultraviolet ray (depicted with a dashed dotted line in FIG.

4) emitted from the light irradiation device 100 to be focused on the printing medium P. In addition, when the light irradiation device 100 is drawn from the offset sheet-fed printing device 1 along the guide rails 10, 11, an emission surface (namely, the cover glass 102) of the light irradiation device 100 is entirely exposed outwards, so that maintenance may be performed to the light irradiation device 100. Hereinafter, the support instrument of the light irradiation device 100 configured by the first rollers 110a to 110e, the second rollers 120a to 120c, the third rollers 111a to 111e, the fourth rollers 121a to 121c, and the guide rails 10, 11 will be described in detail.

FIG. 5 is a diagram for illustrating configurations of the first rollers 110a to 110e, the second rollers 120a to 120c, the third rollers 111a to 111e and the fourth rollers 121a to 121c of this embodiment. FIG. 5(a) is an enlarged view showing a portion C of FIG. 2, in which the first roller 110c and the second roller 120b are observed in the Y-axis direction. In addition, FIG. 5(b) is a diagram in which the first roller 110c and the second roller 120b of FIG. 5(a) are observed in the Z-axis direction. In addition, FIG. 6 is a diagram for illustrating a state (a first state) where the light irradiation device 100 is accommodated in the offset sheet-fed printing device 1 and a state (a second state) where the light irradiation device 100 is drawn in the X-axis direction. FIGS. 6(a) and (b) are diagrams showing a state where the light irradiation device 100 is accommodated in the offset sheet-fed printing device 1, where FIG. 6(a) is a diagram showing the light irradiation device 100 of FIG. 4, observed in the Z-axis direction (a site opposite to the case 101), and FIG. 6(b) is a diagram showing the light irradiation device 100 of FIG. 4, observed in the Y-axis direction (toward the side panel 101a of the case 101). FIGS. 6(c) and (d) are diagrams showing a state where the light irradiation device 100 is drawn from the offset sheet-fed printing device 1, where FIG. 6(c) is a diagram showing the light irradiation device 100 of FIG. 4, observed in the Z-axis direction (a site opposite to the case 101), and FIG. 6(d) is a diagram showing the light irradiation device 100 of FIG. 4, observed in the Y-axis direction (toward the side panel 101a of the case 101).

As shown in FIG. 5, the first roller 110c is a rotating member rotating on a rotary shaft 110cx extending in the Y-axis direction from the side panel 101a of the case 101. In addition, the second roller 120b is a rotating member protruding in the Y-axis direction from the side panel 101a of the case 101 and rotating on a rotary shaft 120bx supported by a pair of rotary shaft support members 103a, 103b arranged in parallel to the Z-axis direction. As shown in FIG. 5(a), the roller surface of the second roller 120b is configured to slightly protrude in the Y-axis direction in comparison to the roller surface of the first roller 110c and come into contact with an inner surface of a bottom surface 10c of the guide rail 10, described later. In addition, as shown in FIG. 5(b), the roller surface of the first roller 110c is configured to have a diameter sufficiently greater than an interval of the rotary shaft support members 103a, 103b and is capable of contacting an inner surface of any one of a pair of side surfaces 10b, 10d of the guide rail 10, described later. In addition, when the light irradiation device 100 moves in the X-axis direction, the first roller 110c or the second roller 120b rotates in contact with the inner surface of the guide rail 10, thereby supporting movement of the light irradiation device 100 (namely, facilitating the movement). Each of the first rollers 110a to 110e of the light irradiation device 100 has the same configuration even though their locations in the X-axis direction are different, and thus the first rollers other

than the first roller 110c are not described in detail. In addition, since each of the third rollers 111a to 111e has the same configuration as the first rollers 110a to 110e even though their mounting surfaces are different from those of the first rollers 110a to 110e, the third rollers 111a to 111e are not described herein. In addition, similarly, since each of the second rollers 120a to 120c has the same configuration even though their locations in the X-axis direction are different, the second rollers other than the second roller 120b are not described herein. In addition, since each of the fourth rollers 121a to 121c has the same configuration as the second rollers 120a to 120c even though their mounting surfaces are different from those of the second rollers 120a to 120c, the fourth rollers 121a to 121c are not described herein.

As shown in FIGS. 4 and 6, in the offset sheet-fed printing device 1 to which the light irradiation device 100 of this embodiment is mounted, the guide rail 10 for supporting the first rollers 110a to 110e and the second rollers 120a to 120c and the guide rail 11 for supporting the third rollers 111a to 111e and the fourth rollers 121a to 121c are installed along the X-axis direction from a front panel 5 of the offset sheet-fed printing device 1 to a rear panel 6 thereof. The guide rail 10 and the guide rail 11 are members having substantially the same length as the emission surface of the light irradiation device 100 and are arranged in parallel to the X-axis direction (FIG. 6). In addition, an opening 5a is formed in the front panel 5 to put or take out the light irradiation device 100.

As shown in FIG. 4, the guide rail 10 is a rectangular case-shaped member having a C-shaped section on the Y-Z plane, composed of a pair of side surfaces 10b, 10d and a bottom surface 10c, and the rotary shaft support members 103a, 103b respectively supporting the rotary shafts 120ax to 120cx of the second rollers 120a to 120c as well as the rotary shafts 110ax to 110ex (in FIG. 4, the rotary shafts 110ax to 110dx are not shown) of the first rollers 110a to 110e pass through the opening 10a, and the first rollers 110a to 110e and the second rollers 120a to 120c are accommodated therein (namely, in the case). In addition, similarly, the guide rail 11 is a rectangular case-shaped member having a C-shaped section on the Y-Z plane, and the rotary shaft support members 103a, 103b respectively supporting the rotary shafts 121ax to 121cx of each of the fourth rollers 121a to 121c as well as the rotary shafts 111ax to 111ex (in FIG. 4, the rotary shafts 111ax to 111dx are not shown) of the third rollers 111a to 111e pass through the opening 11a, and the third rollers 111a to 111e and the fourth rollers 121a to 121c are accommodated therein (namely, in the case). In addition, when the light irradiation device 100 is accommodated in the offset sheet-fed printing device 1 along the guide rails 10, 11 (namely, in a state of FIG. 4, FIG. 6(a) and FIG. 6(b)), the roller surface of at least one of the first rollers 110a to 110e and the second rollers 120a to 120c comes into contact with the inner surface of the guide rail 10, the roller surface of at least one of the third rollers 111a to 111e and the fourth rollers 121a to 121c comes into contact with the inner surface of the guide rail 11, and in this state, the light irradiation device 100 is positioned. For example, the light irradiation device 100 of FIG. 4 is mounted with a posture of emitting ultraviolet rays slightly downwards in a right direction, but if the light irradiation device 100 is mounted with this posture, due to the weight of the light irradiation device 100, the third rollers 111a to 111e at a lower side (namely, on the side panel 101b) contact the inner surface of the side surface 11b of the guide rail 11 at a lower side, simultaneously the fourth rollers 121a to 121c contacts the

11

inner surface of the bottom surface **11c** of the guide rail **11** at a lower side, and the first rollers **110a** to **110e** at an upper side (namely, on the side panel **101a**) contacts the inner surface of the side surface **10b** of the guide rail **10** at an upper side, thereby positioning and mounting the light irradiation device **100**.

As described above, the light irradiation device **100** of this embodiment is supported to be movable in the X-axis direction along the guide rails **10**, **11**, and by pulling a handle **104** (FIG. 2(a)) installed at an end of the case **101** in the X-axis direction, the light irradiation device **100** may be drawn from the offset sheet-fed printing device **1** through the opening **5a** (FIGS. 6(c), (d)). As described above, in this embodiment, regardless of a mounting posture (namely, a mounting angle) of the light irradiation device **100**, at least one of the first rollers **110a** to **110e** and the second rollers **120a** to **120c** comes into contact with the inner surface of the guide rail **10**, and at least one of the third rollers **111a** to **111e** and the fourth rollers **121a** to **121c** comes into contact with the inner surface of the guide rail **11**. By doing so, if the handle **104** of the case **101** is pulled in the X-axis direction, at least one of the first rollers **110a** to **110e** and the second rollers **120a** to **120c** contacting the inner surface of the guide rail **10** and at least one of the third rollers **111a** to **111e** and the fourth rollers **121a** to **121c** contacting the inner surface of the guide rail **11** rotate. By doing so, the light irradiation device **100** may be drawn easily with a small load.

As described above, the light irradiation device **100** of this embodiment includes the first rollers **110a** to **110e** and the second rollers **120a** to **120c** on the side panel **101a** and includes the third rollers **111a** to **111e** and the fourth rollers **121a** to **121c** on the side panel **101b**. In addition, at the offset sheet-fed printing device **1** in which the light irradiation device **100** is included, the guide rail **10** accommodating the first rollers **110a** to **110e** and the second rollers **120a** to **120c** and the guide rail **11** accommodating the third rollers **111a** to **111e** and the fourth rollers **121a** to **121c** are installed. In addition, in this configuration, regardless of a mounting posture (namely, a mounting angle) of the light irradiation device **100**, at least one of the first rollers **110a** to **110e** and the second rollers **120a** to **120c** contacts the inner surface of the guide rail **10**, and at least one of the third rollers **111a** to **111e** and the fourth rollers **121a** to **121c** contacts the inner surface of the guide rail **11**. In addition, in this configuration, the light irradiation device **100** may be securely positioned in the offset sheet-fed printing device **1**, and further the light irradiation device **100** may be easily put or taken out along the X-axis direction. Since the light irradiation device **100** of this embodiment may be drawn from the offset sheet-fed printing device **1** as described above, maintenance required for the light irradiation device **100**, for example mopping of the cover glass **102**, may be easily performed.

Even though the embodiment of the present disclosure has been described above as an example, the present disclosure is not limited to the embodiment but may be modified in various ways within the scope defined in the claims. For example, even though it has been described in this embodiment that the light irradiation device **100** is included in the offset sheet-fed printing device **1** as an example of an elongated housing included and used in a device body, the present disclosure is not limited to such use and device but may be applied to an ink-jet head or ionizer (charge removing device) included and used in a printer, a high-frequency high-voltage discharge electrode included and used in a corona treatment device (hydrophilicity enhancer), a spray nozzle included in a cleaning, cooling, humidifying, coating or anti-static device, an air blow nozzle (for example, a slit

12

nozzle or an air knife) included in a dehydration device or a hot blaster heater, a drier or corona device used in a laminate device, or a heater or measurer (for example, a light-intensity meter, a thermometer or hydrometer, or a telemeter) included and used in various device bodies, a camera, a scanner, a toner box, a UV light source, electron beam irradiation device, or the like.

In addition, even though it has been described that a ultraviolet ray is emitted from the light irradiation device **100** of this embodiment, the present disclosure is not limited to the ultraviolet ray, but for example, the present disclosure may also be applied to an irradiation device of another purpose, for example a light irradiation device emitting a white light.

In addition, even though the light irradiation device **100** of this embodiment is configured so that five rows of LED units **130** arranged in the Y-axis direction are disposed in an arc shape and also line-shaped ultraviolet rays respectively emitted from the five rows of LED units **130** are overlapped with each other on the printing medium **P**, the present disclosure is not limited to this configuration. For example, as shown in FIG. 7, a surface of the support member **150A** on which the cooling pipe **140** is disposed may be a flat surface, and optic axes of LED units **130** of each row may be arranged in parallel to the Z-axis direction. In this configuration, a broad ultraviolet ray approximately parallel to the Z axis is emitted from the light irradiation device **100A**, and a predetermined area on the printing medium **P** is exposed. In addition, as shown in FIG. 8, a surface of the support member **150B** on which the cooling pipe **140** is disposed may protrude with an arc shape, and optic axes of the LED units **130** of each row may be arranged to spread with respect to the Z-axis direction. In this configuration, a much broader ultraviolet ray is emitted from the light irradiation device **100B**, in comparison to the light irradiation device **100A** of FIG. 7, and thus a predetermined area on the printing medium **P** is exposed.

In addition, in this embodiment, even though the first rollers **110a** to **110e** and the third rollers **111a** to **111e** are disposed at symmetric locations with the case **101** being interposed therebetween and also the second rollers **120a** to **120c** and the fourth rollers **121a** to **121c** are disposed at symmetric locations with the case **101** being interposed therebetween, the present disclosure is not limited to this configuration. The first rollers **110a** to **110e** and the third rollers **111a** to **111e** may be disposed at asymmetric locations with the case **101** being interposed therebetween, and also the second rollers **120a** to **120c** and the fourth rollers **121a** to **121c** may also be disposed at asymmetric locations with the case **101** being interposed therebetween. In addition, the numbers of the first rollers **110a** to **110e** and the third rollers **111a** to **111e** are not limited to five, and these numbers need not be identical. The numbers of the first rollers **110a** to **110e** and the third rollers **111a** to **111e** may be suitably changed depending on the length of the light irradiation device **100**. Also, similarly, the numbers of the second rollers **120a** to **120c** and the fourth rollers **121a** to **121c** are not limited to three, and these numbers need not be identical. The numbers of the second rollers **120a** to **120c** and the fourth rollers **121a** to **121c** may be suitably changed depending on the length of the light irradiation device **100**.

In addition, in this embodiment, even though when being observed in the X-axis direction, the rotary shafts **110ax** to **110ex** of each of the first rollers **110a** to **110e** and the rotary shafts **111ax** to **111ex** of each of the third rollers **111a** to **111e** are disposed on the same line and also the guide rail **10** and the guide rail **11** are disposed at both ends of the light

irradiation device 100 along the Y-axis direction, the present disclosure is not limited to this configuration. For example, like a light irradiation device 100C according to a modification depicted in FIG. 9, the rotary shafts 110ax to 110ex of each of the first rollers 110a to 110e and the rotary shafts 111ax to 111ex of each of the third rollers 111a to 111e may be disposed on different lines parallel to the Y-axis direction. In this case, the guide rail 10 and the guide rail 11 are disposed at different locations with respect to the Z-axis direction, but the same effects as in this embodiment occur.

In addition, in this embodiment, even though the first rollers 110a to 110e and the second rollers 120a to 120c are disposed on the side panel 101a of the case 101 and also the third rollers 111a to 111e and the fourth rollers 121a to 121c are disposed on the side panel 101b, the present disclosure is not limited to this configuration. For example, like a light irradiation device 100D according to a modification depicted in FIG. 10, a roller fixing member 105 having a "U"-shaped section of the X-Y plane extending along the X-axis direction may be installed at the rear surface of the case 101, the first rollers 110a to 110e and the second rollers 120a to 120c are disposed on a wall 105a of the roller fixing member 105, and the third rollers 111a to 111e and the fourth rollers 121a to 121c may be disposed on a wall 105b of the roller fixing member 105.

In addition, in this embodiment, even though the guide rail 10 and the guide rail 11 are configured as separate members, both ends of a flat metallic plate 12 may be bent as shown in FIG. 10 to integrally configure the guide rail 10 and the guide rail 11.

In addition, in this embodiment, even though the first rollers 110a to 110e and the second rollers 120a to 120c are disposed on the side panel 101a of the case 101, the third rollers 111a to 111e and the fourth rollers 121a to 121c are disposed on the side panel 101b, and the light irradiation device 100 is supported in the Y-axis direction by the guide rail 10 and the guide rail 11, the present disclosure is not limited to this configuration. For example, like a light irradiation device 100E according to a modification depicted in FIG. 11, the case 101 may extend in the Y-axis direction, the first rollers 110a to 110e and the second rollers 120a to 120c are disposed on the front surface of the case 101, the third rollers 111a to 111e and the fourth rollers 121a to 121c are disposed on the rear surface of the case 101, and the light irradiation device 100 may be supported in the Z-axis direction by the guide rail 10 and the guide rail 11.

Meanwhile, it should be understood that the embodiments disclosed herein are just examples and not intended to limit the present disclosure. The scope of the present disclosure is not defined by the above description but by the appended claims, and all equivalents and modifications of the claims are intended to fall within the scope of the present disclosure.

The invention claimed is:

1. A light irradiation device, which is accommodated in a device body and extends in a first direction on a predetermined irradiation surface in the device body to irradiate a line-shaped light having a predetermined line width in a second direction perpendicular to the first direction, the light irradiation device comprising:
  - a substrate;
  - a plurality of light sources arranged on the substrate at predetermined intervals along the first direction to match an optic axis thereof in a third direction perpendicular to the first direction and the second direction; a box-type case configured to accommodate the substrate and the plurality of light sources;
  - a plurality of first rollers and a plurality of second rollers arranged on a first surface of the case in a row along the first direction; and
  - a plurality of third rollers and a plurality of fourth rollers arranged on a second surface of the case in a row along the first direction,
 wherein each of the first rollers and each of the third rollers has a rotary shaft extending in the second direction and rotates on the rotary shaft,
 wherein each of the second rollers and each of the fourth rollers has a rotary shaft extending in the third direction and rotates on the rotary shaft,
 wherein the first surface and the second surface are parallel to the second direction or the third direction, and
 wherein the case is movably supported between a first state of being accommodated in the device body and a second state of being drawn from the device body in first direction.
2. The light irradiation device according to claim 1, wherein when being observed in the first direction, the rotary shaft of each of the first rollers and the rotary shaft of each of the third rollers are disposed on the same line.
3. The light irradiation device according to claim 1, wherein when being observed in the first direction, the rotary shaft of each of the first rollers and the rotary shaft of each of the third rollers are disposed on different lines.

15

4. The light irradiation device according to according to
claim 1,

wherein a roller surface of each of the second rollers
protrudes further in the second direction in comparison
to a roller surface of each of the first rollers, and a roller
surface of each of the fourth rollers protrudes further in
the second direction in comparison to a roller surface of
each of the third rollers.

5. The light irradiation device according to according to
claim 1,

wherein the number of the plurality of first rollers and the
number of the plurality of third rollers are identical, the
number of the plurality of second rollers and the
number of the plurality of fourth rollers are identical,
the plurality of first rollers and the plurality of third
rollers are disposed symmetrically with the case being
interposed therebetween, and the plurality of second
rollers and the plurality of fourth rollers are disposed
symmetrically with the case being interposed therebe-
tween.

10 15 20
6. The light irradiation device according to according to
claim 1, wherein the device body includes:

16

a first guide rail configured to accommodate and support
the plurality of first rollers and the plurality of second
rollers; and

a second guide rail configured to accommodate and
support the plurality of third rollers and the plurality of
fourth rollers.

7. The light irradiation device according to claim 6,
wherein at least one of the plurality of first rollers and the
plurality of second rollers comes into contact with an
inner surface of the first guide rail,

wherein at least one of the plurality of third rollers and the
plurality of fourth rollers comes into contact with an
inner surface of the second guide rail.

8. The light irradiation device according to according to
claim 1,

wherein the plurality of light sources are arranged to have
M (M is an integer of 2 or above) light sources along
the first direction and to be in N rows (N is an integer
of 2 or above) along the second direction.

9. The light irradiation device according to according to
claim 1,

wherein the light have a wavelength giving an effect to an
ultraviolet curable ink.
